UNITED STATES PATENT OFFICE.

WILLIAM OWEN WEATHERSBY, OF COAHOMA, MISSISSIPPI.

DESIGN FOR A GAME-BOARD.

SPECIFICATION forming part of Design No. 32,139, dated January 23, 1900.

Application filed August 29, 1899. Serial No. 728,926. Term of patent 7 years.

To all whom it may concern:

Be it known that I, WILLIAM OWEN WEATHERSBY, a citizen of the United States, residing at Coahoma, in the county of Coahoma 5 and State of Mississippi, have invented and produced a new and original Design for a Game-Board, of which the following is a specification, reference being had to the accompanying drawings, forming a part thereof.

10 In the accompanying drawings, Figure 1 is a plan view; and Fig. 2 is a transverse sectional view, on line 2 2, Fig. 1.

The distinctive feature of my design resides in a circular base A, having on its upper surface circular rings a, formed by double 15 lines concentric with the axial center of the base, and a plain circle a' at such center, and

also radiating lines a², formed in pairs extending from the said central circle a' to the periphery of base A. The design is clearly shown 20 in the drawings. It will be seen that it is made up of six double circular lines and of twelve double radiating lines.

I claim as my invention—

The design for a game-board, as herein 25 shown and described.

In testimony whereof I have signed my name to this specification in the presence of two subscribing witnesses.

WILLIAM OWEN WEATHERSBY.
